US0D1034191S

(12) **United States Design Patent** (10) **Patent No.:** **US D1,034,191 S**
(45) **Date of Patent:** **** Jul. 9, 2024**

(54) **CONTAINER CAP**

(71) Applicant: **AbbVie Inc.**, North Chicago, IL (US)

(72) Inventors: **Todd Marshall**, Lindenhurst, IL (US); **Marc Plew**, Gurnee, IL (US); **Ted Klikuszowian**, Arlington Heights, IL (US); **Joy Elizabeth Borgardt**, Evanston, IL (US); **James Hughes**, Libertyville, IL (US); **Kelsey M. Coffey**, Evansville, IN (US); **Scott L. Fisher**, Evansville, IN (US); **Jason A. Rowe**, Santa Claus, IN (US)

(73) Assignee: **AbbVie Inc.**, North Chicago, IL (US)

(**) Term: **15 Years**

(21) Appl. No.: **29/721,842**

(22) Filed: **Jan. 23, 2020**

Related U.S. Application Data

(62) Division of application No. 29/601,290, filed on Apr. 20, 2017, now Pat. No. Des. 876,226.
